US00D552739S

(12) **United States Design Patent** (10) **Patent No.:** **US D552,739 S**
(45) **Date of Patent:** **** Oct. 9, 2007**

(54) **MEDICATION MONITOR**

(75) Inventor: **David Alexander Green**, Western Province (ZA)

(73) Assignee: **Simpill (Proprietary) Limited**, Western Province (ZA)

(**) Term: **14 Years**

(21) Appl. No.: **29/235,393**

(22) Filed: **Aug. 2, 2005**

(30) **Foreign Application Priority Data**

Feb. 2, 2005 (ZA) A2005/0105

(51) **LOC (8) Cl.** **24-01**

(52) **U.S. Cl.** **D24/186**

(58) **Field of Classification Search** D24/186, D24/187, 216, 224; D3/203.1–203.3; D9/417, D9/453, 522, 523, 528, 743, 744; 368/10; 700/242–243; 702/177

See application file for complete search history.

(57) **CLAIM**

I claim the design for a medication monitor, as shown and described.

DESCRIPTION

FIG. 1 is a rear perspective view of a medication monitor showing my new design; and,

FIG. 2 is front perspective view thereof.

1 Claim, 2 Drawing Sheets

FIG. 1

FIG. 2
